METHOD OF MAKING SKELETON CRATES

Udo K. Johannsen, Cortland, N. Y., assignor to
 The Brewer-Titchener Corporation, Cortland,
 N. Y., a corporation of New York

Application October 26, 1933, Serial No. 695,304

7 Claims. (Cl. 113—120)

The present invention relates to the art of all-metal containers of the open top framework type designed to be built up from narrow slat iron or so-called strip stock, and includes an improved 5 method for economically fabricating a simple rectangular skeleton crate of the open top type intended to protectively store and bodily transport therein, a group of fragile articles, particularly beverage bottles or the like glassware.

10. Certain of my interspaced upright housing members may herein be extended beyond the level of the respective bottle tops to admit of stacking a large number of such loaded crates in a telescopically centered and laterally stabilized relationship without imposing any load upon the 15 crated contents.

The primary object of my invention is to provide for a sturdy metallic crate of the character indicated in which such structure may be held to the minimum of slat size and weight for prescribed loading requirements, and one capable of 20 withstanding rough usage at the minimum of upkeep charges. A further object is to deaden the inherent tendency toward metallic chatter that is usually encountered in conveying or roughly 25 handling resounding sheet metal containers of the conventional type, also to provide my crate with transversely disposed grillwork serving to maintain bottles or the like contents in an upright 30 position and in compact row formation.

Embodied herein are also other structural features and manipulative steps designed to facilitate the fabrication of my slat iron crate upon an inherently rapid assembly rate and a corresponding 35 low-cost productive scale, all of which aspects will hereinafter be more explicitly pointed out. Reference is had to the accompanying two sheets of drawings which are illustrative of a preferred embodiment, and in which drawings:

40. Fig. 1 shows an elevational side view of my assembled crate, while Figs. 2 and 3 respectively disclose an end view and a top view thereof.

Figs. 4 and 5 are partial sectional views, respectively taken along lines 4—4 and 5—5 of the 45 aforesaid figures.

Fig. 6 fragmentally illustrates certain assembly and welding steps associated with my housing straps, and Fig. 7 schematically depicts a press for subsequently forming the slat ends into housing 50 uprights.

Fig. 8 details an alternately twisted strip stock element for making my bottle spacer grill and Fig. 9 shows an assembled separator unit as made up from such elements.

55. Fig. 10 represents a plan view of an endless

housing hoop and Fig. 11 a special tool for smoothly shaving off the butt weld thereof, while Fig. 12 is a modified hoop provided with a grip portion as used to trim the top of my crate.

Fig. 13 depicts a modified panel that is removably sprung between certain crate hoops.

A detailed description will first be directed to the structural features of my crate as an article of manufacture. As collectively illustrated in Figs. 1 to 5, the housing bottom comprises complementary pairs of thin, laterally spaced slat irons such as 10 and 11, which are disposed flatwise and in crosswise latticed but non-interwoven formation, the respective extended end regions of such slats being sharply kinked to constitute L 15 shaped housing uprights such as 12 and 13. Certain of these upturned slat legs are embraced within a plurality of strap iron hoops, of which the endless bottom hoop 14 may be raised above the lowermost face of said latticework by a 20 comparatively small spacer distance designated as "S". The respective upright extremities are similarly embraced by a top hoop 15 which, for stacking purposes, is preferably kept of a perimetric size somewhat larger than the hoop 14. The intermediate hoop 16 may be identical in size with the bottom hoop. The respective hoops may be 25 parallelly spaced with an embossed name plate or other suitable panel 17 interposed therebetween of which the free edges may be clenched at 18 30 around the respective contiguous uprights, as shown in Fig. 1.

Respectively spanning the confines of the bottom and the intermediate hoop is a separate grillwork, each comprising a plurality of alternately 35 twisted strip stock elements that are crossedly meshed in a manner corresponding to the housing latticework but disposed in straddling registration thereto, to the end that when standing erect upon the housing bottom, each bottle 19 will be 40 adequately upheld within a pair of such grill meshes and separately retained against sidewise displacement.

The complementary ends and sides of my crate may respectively be given a similar configuration. 45 Opposite ends of the top hoop are shown deformed to provide for a pair of rounded grips 20 for lifting purposes, and in these particular regions, the housing uprights may be cut away to afford suitable hand holes such as 21. Intermediate said grips, the top hoop is equipped with a crossbar 22 arranged to augment the lateral rigidity of the crate and also to provide for a supplementary lifting handle. This bar is 50 purposely inset and kept depressed beneath the 55

uppermost face of the top hoop 15 to allow of unobstructedly centering and stacking a number of loaded crates thereover that are respectively entered by the aforesaid distance "S" in the telescopic fashion indicated at 23. It is preferred to have the bottom hoop 14 of a superimposed crate act as a stop medium by resting directly upon the upturned leg ends of the U shaped housing slats of the crate therebeneath as shown in Fig. 4.

As a further refinement, it is preferred to cross-sectionally dish and thereby reenforce the upper region of the respective uprights as at 24 in order to laterally stiffen such columnlike supports against a heavy downward thrust, it being common practice to stack such loaded crates to a considerable height in transport or for bottle storage purposes. As will be understood, the described crate elements are intended to be spot welded, riveted or otherwise secured together in certain of their crossover regions to constitute a unitary structure.

Having defined the article, its preferred mode of fabrication is as follows:

Referring now to Fig. 6, which is illustrative of a preferred step in the making of my crate housing, this shows two mated series of slat irons 10' and 11', that may respectively be severed from reeled strip stock into suitable lengths and thereupon have their respective medial regions laid crosswise into a non-interwoven latticed pattern including a plurality of overhanging slat extensions 12' 13' that originally lie in a common plane with such latticework, as shown. At each crossover region, it is preferred to indent one of the respective slats to provide therebetween for a conventional welding tit as at 25. At the time of striking up such localized tit projections, certain of the slat terminal regions may also be laterally reenforced at 24, except where the cited hand hole provision calls for the use of shortened slats.

To facilitate the rapid assembly of such housing elements, resort may be had to a suitable 45 grooved locating jig or fixture 26 as represented in dotted outline and provided with an access aperture 27 that circumscribes the respective slat crossover points. The respective ends of the rectilinear slat iron portions 10' and 11' extend outwardly to provide for the making of the housing uprights. While positively retained by the jig, such flat latticework may be simultaneously spot welded through said jig aperture in certain tit regions by means of a special multiple 55 welding machine of the ram type.

Thereupon, such interconnected structure is bodily removed from its fixture and subjected to a forming operation by the use of the press shown in Fig. 7. Said press may comprise a 60 platen 28 and a suitable ram member 29, which latter may be equipit with a retractable retaining plate 30 and a circumscribing ringlike punch member 31 arranged to simultaneously kink and thereby throw down all of the overhanging slat ends such as 12' and 13' into the depending right angular relation that is represented by dotted outline in Fig. 7.

Attention will now be directed to the making of my oblong housing hoops, which as depicted in Fig. 10, may be formed up by the use of a four point bending machine into an endless round cornered, configuration having abutting strap ends that are preferably flash welded together. In order to eliminate the usual grinding operation, 70 the resulting flash enlargement indicated at 32,

is herein shaved off in an improved manner by resort to a special shearing implement. This device is preferably of the hinged jaw type and may comprise a pair of separable dies such as 33 of Fig. 11 adapted to snugly embrace the cross-sectional profile of the strap iron. By entering the welded hoop between the closed jaws and forcing said dies lengthwise along the strap iron while the weld is still hot, all superfluous flash metal is readily shaved off to present a neat and 10 smoothly finished joint trim.

As intimated, the bottom hoop 14 and the intermediate hoop 16 are preferably kept identical in perimetric size and each equipit with a spanning separator grillwork as indicated in full 15 lines by Fig. 9. By the use of an automatic flat wire machine of the four slide type, alternately twisted grill elements 34 and 34' of the kind fragmentally shown in Fig. 8, may be cheaply fabricated from reeled strip stock and have their 20 respective ends offset to constitute a welding foot lug such as 35. Elements of suitable overall lengths are then jig assembled as in Fig. 9 and thereupon spot welded at the respective cross points in a manner substantially identical with 25 that described in connection with Fig. 6. Such a separator grill is thereupon inserted into either the hoop 14 or 16 when the respective foot lugs 35 may be welded to the circumscribing strap to constitute a unitary traylike structure of the 30 meshed type, through which bottles or the like may be freely centered. It will be observed that between each pair of adjacent bottles, the strip stock is turned edgewise to allow a compact 35 content disposition, whereas in the crossover regions of said elements, the strip stock is turned flatwise to facilitate the superimposed welding thereof.

The top hoop 15 being devoid of such a grill, is given a somewhat different treatment. As will 40 be apparent from Fig. 12, the opposite strap regions of this rectangular hoop are axially twisted and then dished to provide for the rounded finger grip 20. Such restricted formation may readily be carried out by means of a suitable press and special dies designed to confine the respective hoop corner regions against twist while both grips are being simultaneously formed in a single 45 operation by a successive twisting and cross-sectional dishing of the respective grip regions. By use of such dies and in the same operation therewith, the diametrically opposite sides of the 50 hoop may each be given a further localized twisted depression as at 36, preparatory to receiving the crossbar 22 therebetween. The 55 kinked length of certain end uprights is purposely shortened to provide for the desired hand hole clearance beneath the respective grips.

Having completed the making of the component crate members, these essentially comprise the following subassemblies, viz: a built-up housing provided with interspaced uprights, a pair of unitary hoop trays, and a finishing top ring. Assuming the processed housing members to be 60 placed in their normal upright position, then the externally disposed bottom hoop may first be sprung downward into place over the free ends of its various still flexible uprights 12 and 13, which brings the spaced grill separators into a laterally staggered relation to the crossed bottom slats of the housing as shown in Fig. 3. When located to provide for the inset distance "S", this hoop may then be fixed welded or riveted in place.

As a next step, the inturned edges of the panel 75

17 when used, may be slid down along registering uprights which may in turn be followed by the intermediate hoop 16 and its spacer grid until said superimposed hoop rests snugly upon the 5 complementary panels, whereupon it may likewise be fixedly secured to the embraced upright slats. Finally, the top hoop 15 may be sprung into place and securely welded. Where needed, the cross-bar ends may be nested into the hoop 10 depressions 36 and fastened thereto. It is emphasized that the described welding operations greatly facilitate fabrication in that the component all metal crate elements are rapidly secured together while positively positioned and 15 without need of any punching or drilling of the strip stock.

An outstanding feature of the present innovations resides in the use of reeled strip stock for cheaply producing a high class, competitive crate, 20 designed to provide ample strength for intended purposes without becoming cumbersome in weight. In addition, the exterior contour of such built-up housing is devoid of all sharp projections that might otherwise lead to annoyance 25 in the handling or stacking of heavily loaded crates. It is thought unnecessary to specifically illustrate the cited well known types of fabricating instrumentalities through which my improved process may be expedited. When crate 30 stacking is not a requirement, it may be deemed advisable to dispense with the described superstructure and substitute therefor, a two-high ring assembly in which the features of the top hoop 15 and the intermediate hoop 16 are similarly 35 combined.

As an alternative step in the previously described process, the various housing slat elements may each be initially kinked into U shape, then 40 jig assembled as such and thereupon simultaneously welded in certain of their yoke crossover regions. As a further modification, reference is made to Fig. 13 in which a relatively thin, metallic panel 17A may initially be dished and given 45 a concavo-convex profile such as is represented in dotted cross-sectional outline. Upon being flattened, the panel is then snugly sprung into place between and behind the contiguous hoops 14 and 16 as shown, which correspondingly modifies the previously described assembly sequence, 50 By the use of such panel, stock crates may be completely finished including the painting or galvanizing thereof, and have a suitable name plate with an ownership inscription fixedly attached thereon after each such crate is otherwise made 55 ready for delivery or shipment.

Other advantages inherent in my crate assembly are believed apparent to those skilled in this art, it being obvious that the same underlying structural principles may be utilized in associations other than for bottle containers and that 60 various alterations in design may readily be resorted to in likewise carrying out my illustrative embodiment, all without departing from the spirit and scope of my invention heretofore described and more particularly defined in the appended 65 claims.

I claim:

1. The method of fabricating a skeleton crate and which method consists in the following steps, 70 viz: severing from strip stock, two mated series of substantially rectilinear slat elements each having a finite length; by the use of jig means laying the respective medial regions of one such series of elements into superimposed crosswise 75 relationship over the other series of elements

to constitute an assembled planiform latticework of non-interwoven pattern including a plurality of overhanging slat extensions that are retained against endwise movement by said jig; then while thus retained, positively interconnecting certain of such crossover regions to constitute a unitary latticed structure bodily removable from said jig; thereupon, simultaneously kinking certain of said slat extensions into angular relation with respect to the plane of the aforesaid latticework; providing for a hoop perimetrical 10 sized to embrace the kinked extensions and placing the hoop therearound; and lastly, securing certain of the embraced slat portions to said hoop. 15

2. The process of fabricating an all-metal skeleton crate and which process consists in the following steps, viz: severing from strip stock, two mated series of substantially rectilinear slat elements each having a finite length and by the use of jig means laying the respective medial regions of one such series of elements into superimposed crosswise relationship over the other series of elements to constitute an assembled planiform latticework of non-interwoven pattern including a plurality of overhanging slat extensions that are retained against endwise movement by said jig; simultaneously welding together certain of such latticed crossover regions; thereupon kinking the slat extensions into a common angular relation with respect to the plane of said latticework; providing for a hoop perimetrical 20 sized to embrace said kinked extensions and placing the hoop therearound; and lastly, securing certain of the embraced slat portions to said 25 hoop. 30

3. The method of fabricating a skeleton crate and which method consists in providing for two mated series of slat elements; by the use of jig means laying the respective slat series into superimposed crosswise relationship to constitute an assembled planiform latticework of non-interwoven pattern including overhanging slat extensions that are retained by said jig against 40 endwise movement; then positively interconnecting certain of the latticed crossover regions; thereupon similarly kinking the respective slat extensions into L shape leg formation; providing for a pair of hoops perimetrical 45 sized to embrace the respective kinked legs of such slat extensions; spannably inserting a meshed grillwork within each such hoop; placing the respective hoops around said legs and entering a leg terminal through a contiguous mesh of each such grillwork; and lastly, securing certain of said 50 legs to a circumscribing hoop. 55

4. The method of fabricating a skeleton crate and which method consists in the following steps, viz: providing for one series of metallic slat elements, comprising relatively long and short 60 lengths and also providing for a companion series of slat elements; by the use of jig means assembling the respective medial regions of said one series into laid superimposed crosswise latticelike disposition with respect to the companion 65 slats to constitute a non-interwoven pattern having a plurality of relatively short and long slat extensions that oppositely overhang such latticework and which extensions are respectively retained against endwise movement by the jig 70 means; welding together certain of such latticed crossover regions and thereupon kinking all of the aforesaid extensions into a common L shape relative to their respective medial slat regions; providing for a hoop perimetrical 75 sized to em-

brace the terminal regions of such relatively long kinked extensions and placing the hoop therearound outwardly beyond the extremities of the relatively short kinked extensions.

5 5. The method of fabricating a cratelike structure and which method consists in providing mated series of slat elements assembling the respective slat series into crosswise relationship to constitute a relatively flat latticework including 10 overhanging slat extensions; then positively interconnecting certain of the latticed crossover regions; thereupon similarly kinking the respective slat extensions into L shape; providing for a metallic straplike hoop of rectangular contour 15 sized to embrace certain leg ends of said kinked slat extensions; axially twisting a localized region of said hoop and then cross-sectionally dishing such region to form up a grip portion; and thereupon, placing the hoop around the aforesaid legs 20 and securing the hoop thereto.

6. The process of making a skeleton structure and which process consists in providing for two mated series of slats of which one such series has a slat terminal region laterally reenforced by a 25 cross-sectionally dished formation; assembling the respective series of slats in laid superimposed crosswise latticelike disposition of non-inter-

woven pattern with the respective reenforced slat terminal regions extended outwardly beyond such latticework; then positively interconnecting certain of the latticed crossover points; then kinking the extended slat portions inwardly of 5 their respective reenforced terminal regions; providing for a hoop perimetrically sized to embrace the kinked extensions and placing the hoop therearound; and lastly, securing certain of the 10 embraced slat portions to said hoop.

7. The method of fabricating a skeleton crate and which method consists in providing mated series of slat elements; assembling the respective slat series into crosswise relationship to constitute a relatively flat latticework including 15 overhanging slat extensions; then positively interconnecting certain of the latticed crossover regions; thereupon similarly kinking the respective slat extensions into L shape; bending up metallic strap stock into hoop shape that is perimetrically sized to embrace certain leg ends of the upturned slat extensions and then welding together the abutting hoop ends; shaving off the superfluous welding flash; and thereupon placing said hoop around the aforesaid legs and 20 securing the hoop thereto.

UDO K. JOHANNSEN.
